EDWARD S. HIDDEN, OF MILLBURN, NEW JERSEY.

Letters Patent No. 99,892, dated February 15, 1870.

IMPROVEMENT IN RELAYS FOR TELEGRAPHIC INSTRUMENTS.

The Schedule referred to in these Letters Patent and making part of the same.

To all whom it may concern:

Be it known that I, EDWARD S. HIDDEN, of Millburn, in the county of Essex, and State of New Jersey, have invented certain new and useful Improvements in Relays, as they are sometimes termed, being instruments which break and make electro-magnetic circuits, when another electro-magnetic circuit is broken or closed.

Such instruments are usually employed in connection with long circuits reaching from one place to another, in such manner that when such long circuit is opened or closed, it shall act upon the relay so that the latter shall open and close a short or local circuit at the locality where a telegraphic message is to be received.

The idea of opening and closing one circuit by means of the opening and closing of another, and of using a short circuit to work the telegraphic recorder, was originated by Morse, and he also devised the first relay.

Since his time many such instruments have been devised, and, among others, various forms of an instrument specially described in the English patent granted to George Little, No. 1,053, A. D. 1867.

My instrument embodies many of the features of the instrument described in that patent, and some of the features of a recording instrument described in English Letters Patent No. 2,960, A. D. 1867, granted to William Robert Lake.

These patents are referred to in order materially to shorten my description.

In the drawings making part of this specification—

Figure 1 is a vertical section through the whole contrivance in the preferred form;

Figure 2 is a similar vertical section of the same apparatus without the leveling contrivance;

Figure 3 is a magnified section of the fork or trident of fig. 2; and

Figures 4 to 10, both inclusive, are sketches exhibiting modifications of parts of the contrivance which will hereafter be referred to.

The moving instrument in the relay, which makes and breaks the secondary circuit, is to be in all cases a float arranged in a reservoir containing liquid, which is surrounded by a coil, the coil and float being similar to those described in the patents referred to, and the float being caused to move up and down, as set forth in those patents; but I prefer to use a glass float, as especially described in Lake's patent inclosing one or more permanent magnets, or one or more wire rods, capable of being magnetized by induction, and by preference smaller in size than the one described by Lake.

The reservoir in which the float moves is by pref-

erence like that described as preferred in the same patent, except that it has no regulating tube, and is partially composed of glass, so that not only the vibrations, but the normal position of the float may be ascertained by inspection.

This float, as it moves up and down, makes and breaks the secondary circuit, and its oscillations may be to a certain extent regulated and controlled by permanent adjustable magnets, as described in the patents before referred to.

In the drawings, the reservoir is shown at *a a a*, the glass part at *a¹ a¹*.

I prefer to make it open at bottom and air-tight, and to insert in the top a movable stop, by preference a screw, *a²*, packed by a collar and nut, or in other suitable manner, and at the bottom I make a bridge, *a⁵*, which is a flat rod with a hole in the center, crossing the cylindrical opening diametrically.

I prefer to make the reservoir circular in all its cross-sections, the lower part being inclosed in the coil *b b*, which is by preference contained in a coil-box, and connected with the long circuit, as specially described in the Pen patent of Lake, one end of the wire forming the coil being connected with the insulated ring *b' b'*, and thence through the wire *c*, which bears upon the ring, with the standard *c²* in fig. 1, or *c¹* in fig. 2, and the other end of the coil being in connection through the box with the standards *c³* of figs. 1 and 2.

The reservoir is to be filled wholly or partially, the latter by preference, with a suitable fluid, and in it is located the float *d*, with its inclosed magnets.

To the lower part of the float is to be attached a fork or trident *e e*, figs. 1, 2, and 3. (See also for modifications thereof figs. 4, 5, and 6)

I prefer to make this fork of platinum and of a piece of metal distinct from the magnet or rod contained in the float, but I sometimes intend to fork the rod or magnet, in which case the fork and magnet will be all in one piece, and I prefer that the prong or prongs connecting with one cup, hereafter described, should be longer than the prong or prongs connecting with the other cup, and also to make one prong in the axial line of the stem of the float. This prong is to pass through the aperture in the bridge, and is guided by it, and the trident or fork may be attached to the glass stem by a little wax or cement.

Below the reservoir lie two cups *g g*, one in connection with each pole of the secondary or local circuit, by means of bent rods or wires *d' d'*, and I prefer to make one of these cups annular surrounding the other.

There is an interval between the tops of the cups and the bottom of the reservoir, and I prefer this construction, as it gives free access to the cups and

the prongs, and enables the operator to see all motions of the prongs, and also their normal position, and thus facilitate adjustment, but I sometimes intend to let the bottom of the reservoir touch and be in connection with the cups, so that no fluid can escape between them, and in that case make an opening closed by a small screw like a^2 in the top of the reservoir, through which it can be filled. The cups are to contain mercury.

The vibrations of the float upward are to be checked by the adjustable stop. Its oscillations may to a certain extent be governed by a permanent magnet, adjustable in the cavity of the stop, and another permanent magnet below the float may also be applied, as described in Lake's patent.

I prefer to make the cups adjustable with reference to the reservoir, and the best plan is to cut a screw upon the block in which the cups are formed, which is embraced by a nut, h .

This nut has a flange underlying another flange, k , formed in another nut, screwed to the bed-plate l .

A screw plug, m , holds up the flange on h , and by means of m , this flange can either be jammed fast, or its rotation permitted under considerable friction.

By turning the nut h , the block in which the cups are formed may be raised and lowered, the block being prevented from revolving either by the rods d d' , which are slightly flexible, or by any device which will prevent rotation while it admits of vertical movement.

By examination of the drawings and this description, it will be perceived that provisions are made for limiting the length of vibration of the float, and for adjusting the cups or equivalent thereof, such as amalgamated buttons, with relation to the normal position of the float, and also that in the preferred form there is an open space between the reservoir and the cups, all of which points are advantageous in the use of the instrument.

The great peculiarity of the contrivance, however, may be defined as follows, viz: That in it the points, wires, or prongs, connecting with the two cups of the local circuit, are to be at the same end of the float while the float is surrounded, and can be worked by a single coil.

In the Little patent, the rule of construction is that the two connections with the local circuit shall be at opposite ends of the float.

The exception is represented at fig. 6 of that patent, where the connections are both at the lower end of the float, but in that case the prongs are wide apart, and necessarily so, as two coils are employed, each enclosing one of the prongs.

The rule of construction of my apparatus is, under all modifications thereof, that the connections shall both be at the same end of the float, and so arranged in reference to the latter, and its magnet or magnets, that it can be worked by a single coil.

In a long course of experiments with various forms of Little's apparatus, I have discovered that it is not always reliable when feeble currents come over the main line, owing to the fact that the connections between the wires of the local circuit may be made and broken by the pendulum-like swinging or oscillating motion of his floats, as well as by the up and down motion derived from the coil.

This fault is especially observable when the up and down movements are rapid and of small extent, and under such circumstances this relay is most required. This fault was clearly traceable to the arrangement of the connections at opposite ends of the float, but the same fault exists in fig. 6, where the prongs, although both at one end of the float, are so wide apart that a feeble oscillating motion will much impair the usefulness of the apparatus.

After a long course of experiments I devised the

plan of two prongs at the same end of the float, so near together that the oscillating motion does not effect their position with reference to the mercury in cups, and so combined with the float that the latter may be and is worked by a single coil.

Experiments with this apparatus have proved to me that it is a great improvement upon Little's, and I have further improved upon its reliability by combining a guide, namely, the aperture in the bridge, with the float and prongs, at a point near the end of the prongs, it being clear that by the use of such a combination even wide oscillations of the float bulb will but little alter the relative level of the prongs.

The whole apparatus is to be worked or used, and its various parts will act as described in the Little patent, and I prefer for obvious reasons to level the stand l , before putting it in operation.

In order to do this readily, and as far as possible to prevent careless operators from neglecting this precaution, I attach the stand l of fig. 1, to gimbals, just as an ordinary mariner's compass is attached, the outside pivots of the ring being mounted in columns, as clearly shown in fig. 1.

A heavy weight, such as q , is attached to the stand, by preference to the nut m of fig. 1, and the apparatus will then level itself.

Binding screws such as s s may be used to steady the weight. After it has settled into the position required by gravity, I sometimes intend to use prongs at the upper end of the float, as illustrated by figs. 7 to 10, inclusive, but the prongs should be closer together than there drawn, and the reservoir then becomes a tube open at top and closed at bottom. And I also intend to use two prongs, to make connections with one of the cups, and one with the other, as illustrated, but I prefer two prongs only, and although they may be of the same length and dip into two cups, the mercury in which is at the same level, I prefer either to make the prongs of different lengths, or to use a different level of mercury in the cups, and thus work with one prong always in the mercury.

I claim as of my own invention—

1. The combination of a float with a reservoir and single coil and two prongs and cups, both at the same end of the float, the combination being and acting substantially as described.

2. The reservoir, open at bottom, in combination with a float and prongs and cups arranged below the reservoir, the combination being substantially such as specified.

3. In combination with the relay, as described, the leveling contrivance, as specified.

4. In combination with a reservoir open at the bottom and a float and prongs, two mercury cups, adjustable vertically with reference to the reservoir, substantially as described.

5. In combination with a float, reservoir, and coil, all substantially such as described, a guide applied to the float near the end thereof where the prongs are located, substantially as specified.

6. The cups, with a screw on the outside thereof, in combination with the revolving nut and the connecting wires, which prevent revolution and permit vertical movement of the cups, and in combination with these elements the jam-screw plug and the flanges, whereby the nut may be jammed, as described.

7. The weight attached to the screw-plug, when the nut in which the latter rests is supported by gimbals, as described.

In testimony whereof I have hereunto subscribed my name.

E. S. HIDDEN.
